UNITED STATES PATENT OFFICE.

SAMUEL R. JENNINGS, OF SOUTH BEND, INDIANA.

DESIGN FOR A CAN-OPENER.

SPECIFICATION forming part of Design No. 25,455, dated May 5, 1896.

Application filed February 14, 1896. Serial No. 579,320. Term of patent 7 years.

To all whom it may concern:

Be it known that I, SAMUEL R. JENNINGS, a citizen of the United States, residing at South Bend, in the county of St. Joseph and 5 State of Indiana, have invented and produced a new and original Design for Can-Openers, of which the following is a specification, reference being had to the accompanying drawings, forming part thereof, in which—

10 Figure 1 is a perspective end and side view of my design for a can-opener. Fig. 2 is a bottom plan view thereof; and Fig. 3 is a section on line 3 3 of Fig. 1, these three views being necessary to fully illustrate my design.
15 The leading feature of my design consists in the base-plate B, which is lance-shaped in form, one end thereof being much larger than the other, as shown at b and b², and the sides thereof being provided with projecting points 20 b³, and this plate is provided upon the upper side thereof with a scroll D, which serves as a handle and extends from the larger end of the lance-shaped bottom plate to the smaller end thereof, and the body portion of which 25 near the larger end is scroll-shaped in cross-section, or rather in the section of an ogee curve, as shown in Fig. 3. The scroll D is depressed from the larger end downwardly and outwardly to the smaller end b of the 30 lance-shaped bottom plate, and the larger end

is provided with an inwardly-directed curve d, the base of which extends outwardly to the point b² and above the inwardly-directed curve. The end of the scroll D is almost circular in form, as shown at d². 35

Formed in or secured to the base of the bottom plate B, and near the central portion thereof, is a depending prong or projection C, and adjacent to one of the corners b³ is a depending blade E. 40

The bottom plate and the scroll D constitute the chief features of my new and original design, which is ornamental in appearance, and the principal lines thereof constitute regular curves, the sides and ends of the lance-shaped bottom plate being also inwardly curved, as shown in Fig. 2. 45

Having fully described my invention, I claim as new and desire to secure by Letters Patent— 50

The design for a can-opener, substantially as herein shown and described.

In testimony that I claim the foregoing as my invention I have signed my name, in the presence of the subscribing witnesses, this 10th day of February, 1896. 55

SAMUEL R. JENNINGS.
